HORACE DUMARS, OF NEW SUFFOLK, NEW YORK, ASSIGNOR, BY DIRECT AND MESNE ASSIGNMENTS, OF TWO-THIRDS TO BOWEN-DUMARS POWER CORPORATION, OF NEW YORK, N. Y., A CORPORATION OF NEW YORK, AND ONE-THIRD TO HERMANN F. CUNTZ, OF NEW YORK, N. Y.

NATURAL-GAS LIQUEFACTION

Application filed September 8, 1922. Serial No. 586,996.

This invention relates to the liquefying of natural gas. More particularly it relates to the process of converting natural gas into a relatively safe liquid whereby it may be transported to localities where it may be profitably used as a gas and under suitable conditions may be used in a double or treble aspect, namely, by utilizing the refrigerating effect when it has reached its destination and the liquid is allowed to expand and return to a gaseous stage, or partly in this manner and partly by using the gasified liquid under its pressure created by gasification, in order to produce power.

In the research of many years and experience due to active work when air was first liquefied commercially, and with much knowledge of the many difficulties and intricate questions involved in the liquefaction of different gases, the present invention has been the discovery of the possibilities of utilizing all of the factors that are involved in the character of natural gas, as well as the condition under which such gas is won from the ground.

It is known that others have endeavored to compress natural gas and in so doing have compressed the gas, and by the increased pressure of the natural gas, the constituents, hydrocarbons making up natural gas, have been changed and the changes have been such that their deleterious content finds its way into the resultant liquid. This deleterious effect due to the compression of natural gas is of various aspects, including the dissociation to a more or less extent, of the qualities of the gas, but also creating some extremely explosive chemical compound which in either or both respects make such attempts commercially impractical or abortive for any practical use or after use of the gas, and more particularly preclude the possibilities of safe transport. The excessive pressure may in part, have the effect of cracking on the same general principles as are involved in the now so-called cracking methods for the treatment of natural oils.

My process aims to overcome all of the difficulties heretofore experienced or contemplated by those skilled in the art, for the pur-

pose of making possible the economical liquefaction of natural gas and its transportation to market and to permit its economic utilization.

I will now describe in detail a specific embodiment of my process which involves the following:

I provide in reasonably close proximity to the natural gas wells, apparatus which in its simplest form may comprise what is known in the art as a temperature interchanger. In certain localities enormous supplies of natural gas are available at a rock pressure running over years uniformly at approximately 1000 pounds, and with the casing construction used and the safety equipment of the wells such gas is available at casing-head at a pressure which I establish for use in my apparatus through suitable connections at a fairly uniform pressure which may be any point between 300 to 1000 pounds. Associated with the temperature interchanger I connect an expansion engine into which the natural gas passes at a predetermined pressure. This expansion engine is so designed that clearance relation to the volume of the cylinder permits the expansion of the gas from the predetermined established pressure to a predetermined pressure such as 60 pounds, which pressure is sufficient to carry away the natural gas into the piping at the plant and to the places of utilization locally where it is required and is moved by the natural pressure.

In the expansion engine the drop, for example, from 300 to 60 pounds would reduce the temperature to something like -130 degrees, but I do not aim to realize this full drop in temperature because the first expansion engine is intended to serve the purpose as hereinafter shown, to rotate the shaft actuating the piston in a second expansion engine. The exhaust from the first expansion engine passes through the heat interchanger through which there passes into a counter-current through an internal tube, a fresh quantum of natural gas moving under the predetermined casing-head exit pressure of, say, 300 pounds, which fresh quantum of gas is therefore reduced in temperature to something

higher than the -130 degrees, but it is still maintained under its 300 pounds pressure until its exit from this single interchanger, passing into a second expansion engine. This second expansion engine is made of greater volume than the first expansion engine and the clearance is proportioned so that the gas entering at approximately -130 degrees, will be expanded to zero pressure, and with such expansion, having this second engine properly dimensioned, the expansion drops the temperature with the drop in pressure, to the point of liquefaction of natural gas which is approximately -263. The dimensions are such it safely can be within the zone of liquid and safely pass the critical point of liquefaction. Having to deal only with the gas, which has previously been analyzed and of a reasonably constant and known quality at casing-head, there will be no other gases to liquefy within the reasonable range of temperatures for which the apparatus is designed to reduce temperature in the second stage, thereby keeping out of the liquid any other liquefied admixtures that mingle with or change the character of the liquefied gas.

Between the casing-head and the first expansion engine there are suitable straining tanks for the purpose of drying and clarifying the natural gas dependent upon the analysis of the gas at the particular casing-head when the process is being operated. This includes the separation of gasoline, or what is thought desirable in order that it may be eliminated as a factor in the liquefaction step and also be eliminated from the gas delivered at market from the liquid transported and expanded for use for refrigeration, power and fuel.

It will be noted that the first expansion engine passes the natural gas without any excessive change in temperature and with a regulated outlet exhaust pressure, so that it may be utilized without any loss whatsoever, so that the first expansion step serves the purpose of what today are necessary expansion valves required at the gas fields to reduce the pressure for commercial local use.

A diagrammatic illustration of one embodiment of my system is shown in the accompanying drawing, in which:

Natural gas at high pressure, such as direct from wellhead, flows through the pipe 1, while a separate supply by a wellhead pressure flows through the pipe 2, each of these leading to opposite ends of a double-acting engine, as, for example, a Corliss engine comprising one cylinder 4, but in effect, for this purpose providing two cooperating expansion cylinder spaces or two effective expansion engines. The valves 5 and 6 cooperate in the usual manner whereby with one closed, as 6, after the admission of the high pressure gas from the well, and valve 7 opens, the gas previously admitted through 6 will expand

and drive the piston 9, expelling the previously expanded gas on the other side out of the valve 7 through the conduit or pipe 12 to the interchanger 13. This gas having expanded, its resultant adiabatic cooling results in gas at a much reduced temperature passing through the interchanger, diagrammatically illustrated at 13, and thereby cools the quantum of gas passing at high pressure from the well through pipe 1. The interchanger may be of any usual construction familiar to those in the art, as, for example, indicated in Patents Nos. 749,040, January 5, 1904, or 1,074,103, September 30, 1913. This pre-cools the quantum of gas passing through the supply pipe 1 at predetermined wellhead pressure, so that their further expansion after passing through valve 6, and driving piston 9, results in a further adiabatic cooling, so that when the piston returns expelling the pre-cooled and further expanded gases out of valve 8, they pass into the trap 14 where the liquefied gases settle and are drawn off by the valve 17, and any surplus unliquefied gas passes through the overflow 15 and is led into storage or to pipe line, with any suitable valve control to meet the particular conditions in any one case. The engine used for expansion may have, as diagrammatically indicated, a piston rod 10 with suitable crosshead, connecting-rod and crank driving a suitable pulley for transmission of power, and with fly-wheel and any usual parts desired for proper transmission or absorption of power and control.

By my utilization of the controlled pressure emanating from the natural gas wells, I utilize a vast amount of natural energy which today goes to waste absolute. The utilization of this pressure by the control and interconnection of steps in my apparatus, converts this energy at no cost whatsoever beyond the initial cost of the apparatus to serve the purpose of liquefying the gas to an extent of 50 per cent or less of the gas passing through the apparatus. The exact proportion of the gas liquefied will depend upon the efficiency of the apparatus with respect to insulation and efficiency of the engines and uniformity of operation and other factors which will be evident to those skilled in the art of manufacture of apparatus.

In the entire process it will be seen that the progress is from higher to lower pressures and at no point is there any recompression, therefore eliminating entirely any question of compressing with the deleterious effects that have heretofore been found, and, furthermore, eliminating the cost of compression or recompression which compression has heretofore been the underlying basis of the production of liquefied gases.

Having produced the liquid natural gas without any compression beyond the natural condition at the well, and without any recom-

pression, the resultant liquor does not have the prohibitive dangers or changed qualities which have been found to preclude any commercial use of compressed natural gas, and therefore I provide suitable means of transport, such as tank cars, which will carry the liquid and deliver the same at market. The transportation methods and the gasification with the refrigerating utilization at market, involve the physical and structural apparatus which may vary materially and will not therefore be specifically described in this particular application.

It will be realized that modifications may be made, and under certain conditions similar results may be effected by variations in the process and apparatus still containing the essential factors necessary for the results hereinbefore set forth. Under certain conditions the equivalent of an expansion engine in one or both steps may be resorted to, but while many similar other essential conditions, a plurality of interchangers may be used particularly when the expansion engines are not actuated in combination as hereinbefore specifically set forth.

Essentially the process involves my discovery of the possibilities of utilizing the now almost entirely wasted pressure energy of natural gas at the wells, and making it perform in a practical and commercial way what heretofore has been the prime and essential cost factor in liquefaction of gases.

While not confining myself to the specific process and apparatus above described, what I claim and desire to secure by Letters Patent is:

The process of liquefying natural gas as delivered at two points from the well, comprising admitting a portion of the gas at well temperature and pressure to an expansion engine, thereby reducing the pressure and temperature of the gas, controlling the temperature and pressure to keep said gas from liquefying in said expansion engine, passing the cooled gas from said expansion device into heat-interchanging relation with the other portion of gas at well temperature and pressure, and admitting said 50 second portion of pre-cooled gas to a second expansion engine, so designed as to expansive capacity to liquefy at least a portion of said gas.

In testimony whereof, I have signed my name to this application, this 7th day of September, 1922.

HORACE DUMARS.
